UNITED STATES PATENT OFFICE.

JOSEPH E. SOMERS, OF WATERBURY, CONNECTICUT.

MOLD FOR CASTING BRASS BARS.

1,219,180.

Specification of Letters Patent. Patented Mar. 13, 1917.

Application filed April 1, 1916. Serial No. 38,258.

To all whom it may concern:

Be it known that I, JOSEPH E. SOMERS, a citizen of the United States, residing at Waterbury, in the county of New Haven and State of Connecticut, have invented a new and useful Improvement in Molds for Casting Brass Bars; and I do hereby declare the following, when taken in connection with the accompanying drawings and the characters of reference marked thereon, to be a full, clear, and exact description of the same, and which said drawings constitute part of this application, and represent, in—

Fig. 1 a front view of a mold for casting brass bars constructed in accordance with my invention.

Fig. 2 a side view of the same.

Fig. 3 a top or plan view.

Fig. 4 a sectional view on the line *a—b* of Fig. 2.

Fig. 5 a vertical sectional view.

Fig. 6 a front view of the mold in the open position.

Fig. 7 a top or plan view of the same.

This invention relates to an improvement in molds for cast brass bars. In preparing brass for rolling into sheets, it is first cast into bars which are subsequently rolled to the desired thickness.

The object of this invention is to provide a mold in which these bars may be conveniently cast, and the invention consists in the construction as hereinafter described and particularly recited in the claims. The mold consists of a back plate 2 and a front plate 3, the back plate formed with forwardly projecting side flanges 4 and 5, and bottom flange 6, the space between the side flanges and the depth of the flanges corresponding to the size of the bar to be cast. Preferably and as clearly shown in Figs. 4 and 7 of the drawings, the edges of the flanges 4 and 5 are beveled, and preferably the upper end of the flange 4 is formed with a notch 13 for the purpose as will herein-after appear. The front plate 3 is formed with a rearwardly projecting flange 7 which sets outside of the flanges 4, 5 and 6 of the back plate so as to form a chamber between the two plates. The upper end of the front plate 3 is cut away and beveled to form a throat 14. By beveling the flanges 4 and 5 a tight joint is formed between the two plates. On one side of the back plate are knuckles 8 and 9, and on the front plate are

knuckles 10 and 11, and through these knuckles a pintle 12 extends so that the plates are hinged together, the knuckles being offset so that when the front plate is turned it will swing away clear from the back plate. Connected to the rear of the back plate are transverse rods 15 and 16, projecting beyond the sides of the back plate and supporting at their opposite ends latches 17, 18, 19 and 20 which engage with transverse rods 21 and 22 mounted on the front plate, and by which the two plates are locked together when in the closed position. Preferably and as herein shown, the rods 21 and 22 are protected by transversely arranged downwardly inclined shields 23 and 24. Pivotedly connected with the top of the back plate is a strainer 25 having perforations 32 in its bottom, which, when the strainer is turned forward, will register with the chamber formed between the two plates. This mold rests upon the floor or other suitable base and may be supported in a vertical position in any desired manner. As herein shown the back plate is formed with undercut guides 26 and 27 between which is a vertically movable slide 28 having hooked fingers 29 and 30 adapted to hook over a suitably supported bar or frame 31. The slide 28 is adjustably clamped to the back plate by means of a set screw 33. Preparatory to casting bars the front plate is folded against the back plate, and the hooks turned forward to lock the two plates together. The strainer is then turned forward and molten brass poured into it so as to discharge into the chamber between the plates and so as to form a bar. When the bar is sufficiently cooled, the strainer is turned back, the hooks disengaged from the front plate, and the front plate swung away from the back plate so as to expose the bar in the chamber. The purpose of the notch 13 is to permit the introduction of a suitable tool or implement to pry away the front plate in case it sticks. When the mold is open the cast bar in the chamber is readily removed. The purpose of the guards 23 and 24 is to deflect away from the mold any metal which might overflow from the chamber or from the strainer.

I claim:

1. A mold for casting brass bars comprising a front plate and a back plate, the side and bottom edges of the front plate formed with a rearwardly projecting flange, the

- side and bottom edges of the back plate formed with a forwardly projecting beveled flange fitting within the flange on the front plate, the said plates formed on one side 5 with knuckles, a pintle extending through said knuckles, whereby said plates are hinged together, transverse rods mounted on the rear of the back plate and on the front of the front plate, the ends of the rods projecting beyond the sides of the plates, and latches pivotally mounted on the rods at the rear and adapted to engage with the rods at the front, whereby the plates may be locked together.
- 10 15. 2. A mold for casting brass bars comprising a front plate and a back plate, the side and bottom edges of the front plate formed with a rearwardly projecting flange, the side and bottom edges of the back plate formed 20 with a forwardly projecting beveled flange fitting within the flange on the front plate, the said plates formed on one side with knuckles, a pintle extending through said knuckles, whereby said plates are hinged together, transverse rods mounted on the rear of the back plate and on the front of the front plate, the ends of the rods pro-

jecting beyond the sides of the plates, latches pivotally mounted on the rods at the rear and adapted to engage with the rods at the front, whereby the plates may be locked together, said front plate also formed with integral transverse shields inclined downwardly over the said rods mounted on the said front plate.

3. A mold for casting brass bars comprising a back plate and a front plate, said plates formed with overlapping flanges, said plates formed at one side with knuckles, a pintle extending through said knuckles whereby the plates are hinged together, transverse rods mounted on the front and back plates, latches pivotally connected with the ends of the rods on the back plate and adapted to engage with the ends of the rods on the front plate, whereby the two plates are locked together, the said back plate formed at its rear with undercut guides, a slide entered between said guides and formed with hooked fingers, and a support for said fingers whereby the molds may be held in an upright position.

JOSEPH E. SOMERS.
